UNITED STATES PATENT OFFICE.

VERNICE BROCK, OF NEW YORK, N. Y.

DESIGN FOR A CONVENIENCE-CASE.

49,173.

Specification for Design.

Patented June 13, 1916.

Application filed January 28, 1916. Serial No. 74,887. Term of patent 3½ years.

To all whom it may concern:

Be it known that I, VERNICE BROCK, a citizen of the United States, residing at New York, in the county of New York and State of New York, have invented a new, original, and ornamental Design for Convenience-Cases, of which the following is a specification, reference being had to the accompanying drawing, forming part thereof.

Figure 1 is a top plan view of the con-

venience case. Fig. 2 is a perspective view thereof.

I claim:

The ornamental design for a convenience case, as shown.

VERNICE BROCK.
